UNITED STATES PATENT OFFICE.

HARRY W. JONES, OF NEW YORK, N. Y., ASSIGNOR TO AMERICAN CAN COMPANY, OF NEW YORK, N. Y., A CORPORATION OF NEW JERSEY.

COMPARTMENT FRICTION-TOP CAN.

1,029,017.

Specification of Letters Patent. Patented June 11, 1912.

Application filed August 19, 1907. Serial No. 389,159.

To all whom it may concern:

Be it known that I, HARRY W. JONES, a citizen of the United States, residing in New York, in the county of New York and State of New York, have invented a new and useful Improvement in Compartment Friction-Top Cans, of which the following is a specification.

My invention relates to improvements in 10 sectional or compartment friction top cans.

The object of my invention is to provide a sectional or compartment can of a simple, efficient and durable construction, in which the bottom head of one section will serve as 15 the closure for the annular head disk of the other section and as a means for securing the two sections together, and in which a gasket or packing may be interposed between the annular head disk of one section and the bottom head of the other section, and in which the upper or supplemental section will have a suitable closure.

My improved can is especially designed 25 for paints having bronze or other powder intended to be mixed with the liquid paint shortly before using, and which it is desired should be kept dry and in a separate compartment from the liquid paint.

My invention consists in the novel construction of parts and devices and in the 30 novel combinations of parts and devices herein shown and described and more particularly specified in the claims.

In the accompanying drawing forming a 35 part of this specification, Figure 1 is a central vertical section of a sectional or compartment can embodying my invention; Fig. 2 is a detail bottom view of the upper or supplemental section, partly in section or 40 broken away; and Fig. 3 is a detail top view of the lower or main section; Fig. 4 is a sectional view illustrating a modification.

In the drawing A represents the body of 45 the main or lower section, the same having, preferably, a lock or other side seam a; B is the annular head disk of said section and C its bottom head. The annular head disk B of the main section has a depending annular friction seat wall b, and preferably also a 50 raised annular bead b¹. The upper or supplemental section D is preferably drawn or seamless, and is finished at its head part d with an annular cap groove or flange d¹ to receive a screw top G. The supplemental 55 section D is furnished with a countersunk

bottom head F, having a depending friction seat wall f snugly fitting the friction seat wall b of the annular head disk B of the main section A and closing the opening therein, and also serving to secure the two 60 sections of the can together. The bottom head F of the supplemental section D is also furnished with a rim portion f¹, preferably provided with a raised annular bead f² on its opposite side, and a corresponding annular groove f³ on its lower face, and also a marginal curved retaining flange f⁴ for the packing H which is interposed between the annular head disk of the main section and the bottom head of the supplemental 65 section. The annular bead or shoulder f² engages the lower end d¹ of the supplemental section D which is soldered or otherwise secured to the bottom head F.

The screw top G is furnished with screw 75 threads g and preferably with an inwardly projecting flange g¹ at its upper end, and the same is closed by a removable screw cap H¹.

g² is a packing disk inserted between the 80 screw cap H¹ and the screw nozzle G of the upper section.

The curved flange f⁴ which retains the packing H on the bottom head F of the supplemental section, also in connection with the marginal flange b² of the annular head disk B of the main section forms a crease 85 for insertion of an implement in prying off the supplemental section, and thus opening the main section.

In the modification illustrated in Fig. 4 the bottom head F of the upper section has its externally projecting pry off rim f⁵ furnished with an upturned flange f⁶ which is folded over a marginal flange d⁵ on the upper section D, the upper section being thus 90 permanently secured to its bottom head F.

In the construction shown in Fig. 4, the gasket or packing disk H is held in place 95 simply by being clamped between the annular head disk of the main section and the bottom head disk of the upper or supplemental section, the two head disks being firmly held together by the tight frictional gripping action of their interengaging annular friction seat walls.

I claim:

1. A sectional or compartment can comprising a main section and a supplemental section, both having openings located at 100

110

their upper ends when assembled, a removable closure for the opening in the supplemental section, the main section having a body and an annular head disk furnished with a depending friction seat wall at its inner edge, said supplemental section having a body and a countersunk bottom head furnished with a friction seat wall coöperating with the friction seat wall of the main section and adapted to close the opening in the annular head disk of the main section, and securing the two sections together, the bottom head of said supplemental section having an externally projecting rim portion extending beyond the body thereof and provided with an upwardly projecting annular shoulder fitting within the lower end of the body of said supplemental section, and the body of said supplemental section being secured at its lower end to said rim portion and extending upwardly therefrom.

2. A sectional or compartment can comprising a main section and a supplemental section, both of said sections being provided with openings at their upper ends when as-

sembled, and a closure for the opening in said supplemental section, the main section having a body and an annular head disk furnished with a depending friction seat wall at its inner edge, said supplemental section having a body and a countersunk bottom head furnished with a friction seat wall coöperating with the friction seat wall of the main section, and adapted to close the opening in the annular head disk of the main section and secure the two sections together, the bottom head of said supplemental section having an externally projecting rim portion extending beyond the body thereof and provided with an upwardly projecting annular shoulder fitting within the lower end of the body of said supplemental section, and the body of said supplemental section being secured at its lower end to said rim portion and extending upwardly therefrom.

HARRY W. JONES.
